UNITED STATES PATENT OFFICE.

CHARLES V. D'OSSONE, OF PHILADELPHIA, PENNSYLVANIA.

DUST-BEATER.

SPECIFICATION forming part of Letters Patent No. 781,814, dated February 7, 1905.

Application filed June 15, 1904. Serial No. 212,639.

To all whom it may concern:

Be it known that I, CHARLES V. D'OSSONE, a citizen of the United States, residing in the city and county of Philadelphia, in the State 5 of Pennsylvania, have invented certain new and useful Improvements in Dust-Beaters, of which the following is a full, clear, and exact description, reference being had to the accompanying drawings, of which—

10 Figure 1 is a side elevation; Fig. 2, an edge elevation.

The object of this invention is to provide a cheap, simple, and efficient device for beating furniture, garments, &c., to remove dust 15 therefrom.

The exact nature of the invention will appear from the following specification in connection with the accompanying drawings.

In carrying out my invention I take a round 20 tubular piece of braided elastic wire 1 of suitable length and set the same by compression in the form of a flattened tube, so that it will form in cross-section an elongated ellipse. I then bend this flattened tube over upon itself 25 about midway of its length, thus having two contiguous superposed limbs 1^a, the free ends of which are brought together and secured to a suitable handle 2.

In using the device the handle is held by the hand, and the garment or other article to be 30 cleaned of dust is struck with the beater flatwise.

The beater is elastic as a whole, and each of the wires being very elastic and there being many of them crossing each other the fabric 35 being operated upon is struck at numerous points, thereby bringing out the dust very effectually, and the wires being also light the beating will not injure the fabric.

Having thus described my invention, I claim 40 as new and desire to secure by Letters Patent—

The hereinbefore-described dust-beater, comprising a flattened tube of elastic braided wire bent upon itself, and having its free ends secured to a suitable handle, substantially as 45 set forth.

In testimony whereof I have hereunto affixed my signature this 23d day of May, A. D. 1904.

CHARLES V. D'OSSONE.
